(57) **CLAIM**

The ornamental design for a coiled sliding duo-lock snap, as shown and described.

DESCRIPTION

FIG. 1 is a front-top perspective view of a coiled sliding duo-lock snap showing my new design;

FIG. 2 is a rear-bottom perspective view thereof;

FIG. 3 is a front view thereof;

FIG. 4 is a rear view thereof;

FIG. 5 is a top view thereof;

FIG. 6 is a bottom view thereof;

FIG. 7 is a right view thereof; and,

FIG. 8 is a left view thereof.
